Inventor:

Lucas C. Clark

United States Patent Office.

LUCAS C. CLARK, OF PLANTSVILLE, CONNECTICUT.

Letters Patent No. 90,995, dated June 8, 1869.

IMPROVEMENT IN TEAPOT-HANDLES.

The Schedule referred to in these Letters Patent and making part of the same.

To all whom it may concern:

Be it known that I, LUCAS C. CLARK, of Plantsville, in the county of Hartford, and State of Connecticut, have invented a new and useful Improvement in Teapot-Handles; and I do hereby declare that the following is a full, clear, and exact description thereof, which will enable those skilled in the art to make and use the same, reference being had to the accompanying drawing, making a part of this specification, which drawing is a side elevation of my invention.

My invention consists in constructing a skeleton teapot-handle of a single piece of cast-metal, the body of which is of a square form, for the purpose of making the sides of the same very thin.

Letters Patent were granted to Enos E. Stow, December 10, 1867, for a hollow, tubular teapot-handle, which is cast in halves, and afterwards secured by the connections which connect it with the vessel to which it is to be attached.

The expense of casting two pieces to obtain one, and then fitting the same together, is no trifling amount.

To produce equally as good an article, at a less cost, is the object of my invention.

I construct the handle A of nearly square form, and thickly perforate the same through from side to side. As the handle is nearly square in form, the perforations can be made so near the edge as to leave the metal outside of the perforations very thin, and of nearly equal thickness the whole thickness of the handle. The perforations are slightly drawing, so that the pattern can be drawn from the sand, and leave the mould of the desired shape. Thus the handle can be cast with the perforations in the same, as shown.

It will be seen that if the handle were formed of the usual round, or oval form, the perforations could not

be as large, without leaving the handle either too weak, or the metal outside of the perforations in the centre of the handle much thicker than it is in the square handle.

On each end of the handle A, I form oval-shaped tenons *a a*, the ends of which are designated by the broken lines.

The scale is removed from a portion of the tenons *a a* in any proper manner, and then a short sheet-metal tube, or connection, *c c*, is placed on each tenon, and secured by solder. The tubes *c c* are then soldered to the teapot.

The connection, as so far described, is similar to Stow's connection, and, therefore, not considered as my invention.

By making the handle A of square form, I am enabled to construct a skeleton-handle, in which the metal is so thin that the circulation of the air will keep the handle cool enough to be handled with bare hands.

By casting the skeleton-handle in a single piece, it can be made at a much less price than the tubular skeleton-handle of Stow's patent.

I do not claim making perforations to allow the free passage of air, as the same is shown in Stow's patent; but

What I claim as new, and desire to secure by Letters Patent, is—

As a new article of manufacture, a skeleton, or perforated teapot-handle, cast in a single piece, substantially as described and for the purposes set forth.

LUCAS C. CLARK.
